UNITED STATES PATENT OFFICE.

WILLIAM F. ARMSTRONG AND FREDERICK S. FORD, OF CHICAGO, ILLINOIS.

SAFETY CAR-LADDER.

1,170,390.

Specification of Letters Patent.

Patented Feb. 1, 1916.

Application filed September 4, 1915. Serial No. 49,062.

To all whom it may concern:

Be it known that we, WILLIAM F. ARMSTRONG and FREDERICK S. FORD, citizens of the United States of America, residing at 5 Chicago, in the county of Cook and State of Illinois, have invented new and useful Improvements in Safety Car-Ladders, of which the following is a specification.

This invention relates to improvements in 10 safety ladders for railway cars whereby the trainmen may ascend to the roof of the car and descend therefrom whenever desired.

In carrying out the present invention, it is our purpose to improve and simplify the 15 general construction of ladders of the class described and to provide a ladder wherein one rung will be formed in such manner as to coöperate with the adjacent side wall of the car in order to reinforce the ladder at 20 this point so that the strain on the latter, incident to the trainmen traversing the same, will be distributed over the ladder evenly and uniformly.

With the above and other objects in view, 25 the invention consists in the construction, combination and arrangement of parts hereinafter set forth in and falling within the scope of the claims.

In the accompanying drawing Figure 1 is 30 a view in front elevation of a ladder constructed in accordance with the present invention, the same being shown as applied to the side wall of a car. Fig. 2 is a view in side elevation of the ladder, the same being 35 shown as applied to the car. Fig. 3 is a fragmentary vertical sectional view through the ladder. Fig. 4 is a fragmentary horizontal sectional view through the car showing the ladder in end elevation.

40 Referring now to the drawing in detail, 1 designates the side rails or stiles of the ladder. Formed in each side rail 1 and spaced apart appropriate distances along such rail are openings 2 alining with the openings 45 respectively in the other rail. The rungs in the ladder are indicated at 3 and each rung is in the form of a bar having the opposite extremities thereof bent inwardly as at 4 and passed through the particular pair of 50 alining openings 2 and the extremities of the inwardly bent portions are bent outwardly at right angles to the main body portion of the rung as at 5 and disposed upon the inner sides of the respective stiles 1, as clearly 55 illustrated in Fig. 4 of the drawing.

Secured to the top and bottom ends of the

stile 1, 1 are certain limbs of right angular brackets 6 and the remaining limbs of the brackets 6 are fastened to the side wall of the car by means of bolts 7, as clearly illustrated in Fig. 2 of the drawing. 60

In accordance with our present invention, the side wall of the car is formed with depressions 9 disposed in the same horizontal plane and spaced apart a distance equal to 65 the distance between the outwardly extending portions 5 of the rungs of the ladder and these depressions are disposed in alignment with the respective outturned portions 5 of one of the central rungs and the outturned portions of such rung are relatively 70 long as compared with the similar portions of the remaining rungs so that the outer ends of such portions will enter the depressions 9. This construction acts to reinforce 75 the ladder at the center thereof and the relatively long outturned end portions of the particular rung seated within the depressions 9 coöperate with the right angular brackets 6 and the bolts 7 to maintain the 80 parts of the ladder in proper relative positions and distribute the strain equally over the ladder.

We claim:

1. In a ladder for railway cars, the combination with the side wall of the car having depressions formed therein and spaced apart longitudinally of such wall, of a ladder comprising side rails spaced apart, brackets at the opposite ends of the respective rails securing the ladder to the side wall of the car, bolts holding said brackets to the side wall of the car, said side rails being formed with alining openings disposed adjacent to the depressions in said side wall, a 85 rung formed of a bar having the end portions thereof inturned and passed through said openings and the inner ends of the inturned end portions bent outwardly and disposed within said depressions and coöperating with said brackets to support the side rails, and rungs disposed upon opposite sides of the first-mentioned rung and secured to the side rails and spaced apart equal distances from each other and from 90 the first-mentioned rung. 95

2. In a ladder for railway cars, the combination with the side wall of the car, of a ladder comprising side rails spaced apart, brackets at the opposite ends of the respective rails securing the same to the side wall 100 of the car, said side rails being formed with 105

- alining openings, rungs each formed of a bar having the end portions thereof inturned and passed through the corresponding openings and then bent outwardly and having
5 the outwardly bent portions bearing against the inner surfaces of the respective rails to hold the latter properly spaced apart.

In testimony whereof we affix our signatures in presence of two witnesses.

WILLIAM F. ARMSTRONG.
FREDERICK S. FORD.
